ASHTRAY FOR EXTINGUISHING CIGARETTES OR CIGARS

Filed May 18, 1935

UNITED STATES PATENT OFFICE

2,063,717

ASHTRAY FOR EXTINGUISHING
CIGARETTES OR CIGARS

Michael Barbire, Huntington Station, N. Y.

Application May 18, 1935, Serial No. 22,166

1 Claim. (Cl. 131—51)

This invention relates to ash trays, and the like, and has to do especially with an ash tray in which is provided convenient and readily accessible means for extinguishing cigarettes or cigars before being discarded or dropped into the tray.

It is accordingly the principal object of this invention to provide an ash tray of this character having a suitably positioned well or container adapted to contain a supply of water or other fire extinguishing fluid for a sponge or other liquid absorbent substance to be retained within said container.

Another object of this invention resides in the provision of a support or pedestal for said container to be rigidly associated with the ash tray.

The various novel features of the invention will be disclosed in the following specification and drawing and particularly pointed out in the appended claim.

20 In the drawing:

Figure 1 is a perspective view of the improved ash tray.

Figure 2 is a detail sectional view through the container portion taken on the line 2—2 of Figure 1.

The ash tray shown herein is made of glass or any other suitable material and comprises the usual ash receiving bowl portion 10 of any desired size or shape provided with a laterally extending flange 11, having the usual depressions 12 formed thereon for holding the cigars or cigarettes, all of which is well known and more or less conventional to all ash trays.

Arranged at one of the sides of the ash tray is a pedestal 13 which is preferably made integral with the body of the ash tray and of the same material, though if desired the same may be formed separable and secured to the ash tray in any desired manner.

The upper part of the pedestal 13 is so formed as to provide a well or container 14 having a wall 15, said well or container being of a substantial depth so that the same may receive an appreciable quantity of water or other fire-extinguishing fluid 16. The upper edge of the wall 15 is provided with a peripheral inwardly directed flange or bead 17, the function of which is to hold the sponge 18 within the well or container.

50 The sponge 18, which may be replaced with any other suitable water absorbent and retaining substance, is of a size as to snugly fit within the well 14, the bottom of said sponge being adapted to lie in the water 16, so as to be continually of the same moisture content.

To provide a support or holder for matches the rear wall of the well or container 14 is elevated as at 19 and is preferably made much thicker and rectangular in plan, the dimensions of the same being such as to snugly fit within the common penny box of matches which is of standard size. Referring to Fig. 2, it will be noted that the rear wall 19 overhangs the pedestal 13 at the rear thereof a distance equal to the overhang of the well at the front of the pedestal to provide a symmetrical construction. The upper end of the wall 19 is provided with a V-groove 20 running transversely of the pedestal 13 to provide a seat for the reception of a packet of book matches.

From the foregoing, it will readily be seen that cigars and cigarettes, as well as matches may be instantly extinguished merely by simply applying the lit end into contact with the moistened sponge, after which the stubs may be dropped into the bowl of the ash tray. When the stubs or matches are thus extinguished all possibility of fire which might result from the overturning of the tray containing stubs which were still lit is prevented. By extinguishing the stubs as described the elimination of all offensive odors and smoke is effected.

In view of the simplicity of construction of the above described ash tray, the sponge may readily be removed and the well, ash tray bowl and sponge cleaned by the simple expedient of washing the same.

The elevation of the well with respect to the ash tray bowl renders the use thereof in the extinguishing of cigars, cigarettes or matches convenient and readily accessible, and also obviates the likelihood of the well becoming clogged with ashes, stubs, etc., to prevent the efficient operation of the sponge therein as an extinguishing medium.

While a preferred embodiment of my invention has been shown and described it is to be understood that the same may be varied and modified in its structural characteristics without departing from the spirit of my invention as herein disclosed. I, therefore, reserve the right to make such changes, as shall fairly fall within the scope of the appended claim.

Having thus set forth and disclosed the nature of this invention, what is claimed is:

An article of manufacture including an ash receiving tray, a vertical pedestal arranged at one side of said tray and formed integral therewith, the upper end of said pedestal being formed to define an open well having front, rear and

5 side walls with the walls thereof so constructed as to extend laterally beyond the walls of said pedestal, the rear wall being of greater thickness than the other walls and extending above the top of said well, and being formed on its top side with a V-shaped groove extending transversely of said pedestal, said extended wall portion being adapted to support either a box or book of matches, said well being adapted to con-

tain an extinguishing fluid and a fluid absorbent means superposed thereon, and a holding means for said fluid absorbent means comprising a horizontally inwardly directed flange integrally formed on the upper peripheral edge of the front 5 and side walls of said well, and extending across the face of said rear wall.

MICHAEL BARBIERE.
